ABSTRACT

In the oxidation of higher α -olefins by means of chromosulfuric acid the corresponding saturated higher aliphatic monocarboxylic acids are obtained in a high yield, if the oxidation is carried out in the presence of from 2 to 15 % by weight of saturated, aliphatic mono- or dialcohols having from 10 to 40 carbon atoms. The carboxylic acids obtained are suitable for preparing wax-like substances.

PROCESS FOR PREPARING HIGH MOLECULAR WEIGHT ALIPHATIC CARBOXYLIC ACIDS BY CHROMOSULFURIC ACID OXIDATION OF α -OLEFINS

The present invention relates to a process for preparing high molecular weight, aliphatic monocarboxylic acids.

The preparation of high molecular weight aliphatic monocarboxylic acids by oxidizing α -olefins having from 16 to 70 carbon atoms in the molecule or technical mixtures of such olefins by means of chromosulfuric acid is known (cf. German Offenlegungsschrift No. 2,165,858). According to this process colourless, thermostable fatty or wax acids are obtained containing, however, a considerable proportion of unreacted starting material. It is moreover known that this proportion may be materially reduced by carrying out the oxidation in several steps (cf. German Offenlegungsschrift No. 2,262,130). In the first step at least 50% by weight of the required quantity of chromosulfuric acid is used, the consumed oxidation agent is then separated and the oxidation is terminated in one or several further steps.

It has now been found that the proportion of unreacted olefin may be further reduced surprisingly by using α -olefins of α -olefin mixtures diluted with small quantities of higher, aliphatic alcohols.

The present invention provides a process for preparing saturated, high molecular weight, aliphatic monocarboxylic acids by oxidizing α -olefins having from 16 to 70 carbon atoms in the molecule or mixtures of such α -olefins in the molten state by means of aqueous chromosulfuric acid, which comprises adding to the molten olefins or mixtures of olefins prior to oxidizing of from 2 to 15% by weight, calculated on the olefins, of aliphatic mono- or dialcohols having from 10 to 40 carbon atoms in the molecule-optionally in the form of their fatty acid esters - and then oxidizing with aqueous chromosulfuric acid.

According to the process of the invention the proportion of neutral matter in the oxidation products, depending on the quantity of chromosulfuric acid and the oxidation method used, may be reduced by 10 to 50% or even more.

Suitable starting materials for the chromosulfuric acid oxidation according to the invention are for example α -olefins having more than 15 carbon atoms in the molecule, for example 1-hexadecene, 1-octadecene and 1-eicosene or α -olefins having up to about 70 carbon atoms, which may be prepared by oligomerizing ethylene. Commercial mixtures of α -olefins having from 22 to 28 or from 24 to 48 carbon atoms are preferably used.

Especially suitable aliphatic alcohols are saturated monoalcohols having from 10 to 40 carbon atoms, preferably straight chain primary alcohols, as for example decyl alcohol, dodecyl alcohol, tetradecyl alcohol, cetyl alcohol and especially stearyl alcohol and behenyl alcohol, moreover glycol- and polyglycol monoalkyl ethers having higher alkyl groups, such as the ether-alcohol glycol-monostearyl ether. Synthetic monoalcohols, for example those, prepared according to the known polyethylene synthesis with Ziegler catalysts followed by oxidative hydrolysis of the aluminium trialkyls are also suitable. Aliphatic dialcohols having from 10 to 40 carbon atoms, for example α , ω -diols, such as 1, 10-decane-diol or 1, 19-nondecane-diol, and option-

ally polyalkylene glycols are also suitable; it should be taken into consideration however that dicarboxylic acids are generally formed in the oxidation of diols, so that the use of diols is not recommended, if the acids resulting from the oxidation shall be free from dicarboxylic acids. Esters of higher monoalcohols or diols with fatty acids having 2,3 or from 16 to 40 carbon atoms, for example stearyl acetate, stearyl stearate and esters of the montanic acid are also suitable. They are first saponified under the oxidation conditions, so that their efficiency finally is based on the presence of the basic alcohols.

The aliphatic monoalcohols or diols are added to the molten α -olefin or α -olefin mixture to be oxidized in an amount of from 2 to 15, preferably of from 4 to 10 % by weight, calculated on the olefins.

The oxidation is carried out in known manner. Chromosulfuric acid containing per liter from 50 to 140 g of CrO_3 , preferably from 80 to 120 g and from 300 to 650 g, preferably from 400 to 550 g of H_2SO_4 , is used as oxidizing agent. The oxidation temperature is in the range of from 60° to 180°C, preferably of from 90° to 120°C. The quantity of oxidizing agent required is from 100 to 250 %, preferably from 120 to 200 % of CrO_3 , calculated on the weight of the olefin-alcohol mixture to be oxidized.

The oxidation is preferably carried out as follows: The molten olefin-alcohol mixture is introduced into the chromosulfuric acid heated to the desired oxidation temperature by small amounts or continuously and the mixture is vigorously stirred during the whole reaction. It is also possible to add the oxidizing agent to the molten mass of the product to be oxidized. According to a preferred method the reaction is carried out in a multiple-stage process, while separating the depleted oxidant after each step. The oxidation times are generally in the range of from 4 to 8 hours.

As soon as the reaction is terminated, which may be determined by titration of the residual CrO_3 , stirring is stopped and the reaction mixture is cooled, whereby the oxidation product and the used up oxidant separate into two layers. The carboxylic acid phase is washed while stirring with diluted sulfuric acid at a temperature of from 90° to 100°C until it is free from chromium III salt and is then washed with water at the same temperature until it is free from sulfuric acid.

The high molecular weight, aliphatic carboxylic acids or carboxylic acid mixtures obtained having a relatively low content of neutral matter are colourless and thermostable and are especially suitable for preparing wax-like esters, partial esters and amides, which may be used as lubricants in the plastics processing and in the preparation of floor waxes and polishing pastes.

The following examples illustrate the invention.

EXAMPLES

100 g each of a commercial mixture of α -olefins having from 24 to 28 carbon atoms were mixed in the molten state with variable amounts of higher, aliphatic mono- or dialcohols and oxidized with chromosulfuric acid containing per liter 100 g of CrO_3 and 540 g of H_2SO_4 , while stirring at a temperature of from 110° to 115°C. The quantity of CrO_3 was in the range of from 125 to 175 % by weight, calculated on the olefin-alcohol mixture used (1.18 or 1.65 liter). In examples 1 and 2 the whole quantity of chromosulfuric acid was first introduced, whereas the oxidation was carried out in a two-stage process in examples 3 and 4, with separation

of the oxidant used up in the first stage. The test dates and the results are listed in the following table.

lated on the olefins, of saturated aliphatic mono- or dialcohols having from 10 to 40 carbon atoms in the

Ex- ample	alcohol added (% by weight)	quantity of chromosulfuric acid (% by weight)			Oxidation product			
		total	first stage	second stage	acid number	neutral matter (% by weight)

²² α, ω -nonadecane diol

What is claimed is:

1. A process for preparing saturated, high molecular weight, aliphatic monocarboxylic acids by oxidizing in the molten state α -olefins having from 16 to 70 carbon atoms in the molecule or mixtures of such olefins by means of aqueous chromo-sulfuric acid, which comprises adding to the molten olefins or mixtures of olefins prior to oxidizing from 2 to 15 % by weight, calcu-

molecule, or their fatty acid esters, and then oxidizing with the aqueous chromosulfuric acid at a temperature of 60° to 180°C.

2. The process as claimed in claim 1, wherein the aqueous chromosulfuric acid used is a chromosulfuric acid containing per liter of from 50 to 140 g of CrO₃ and from 300 to 650 g of H₂SO₄.
